UNITED STATES PATENT OFFICE.

RUDOLPH LIEBMAN, OF NEW YORK, N. Y.

DESIGN FOR A BUTTON.

SPECIFICATION forming part of Design No. 18,505, dated August 7, 1888.

Application filed June 16, 1888. Serial No. 277,381. Term of patent 3½ years.

To all whom it may concern:

Be it known that I, RUDOLPH LIEBMAN, a citizen of the United States, residing at New York, in the county and State of New York, have invented and produced a new and original Design for Buttons, of which the following is a specification, reference being had to the accompanying drawing, forming part thereof.

My invention consists in a new design for buttons, as fully set forth in the following specification and claim and illustrated in the accompanying drawing, which represents a face view of a button containing my said design.

In the drawing, the letter A indicates the button, circular in outline, the face of which constitutes a plain field, a, containing the representation of a horseshoe, B, of a color contrasting with the color of the field. A ribbon-like band, C, extends in a right line entirely across the field and across the horseshoe, and

is of a color contrasting with the color of the field and also with the color of the horseshoe.

What I claim as new, and desire to secure by Letters Patent, is—

In a design for a button having a circular outline, the field a, containing the horseshoe B, of a color contrasting with the color of the field, and the ribbon-like band C, extending in a right line across the field and horseshoe and of a color contrasting with the colors of the field and horseshoe, substantially as shown and described.

In testimony whereof I have hereunto set my hand and seal in the presence of two subscribing witnesses.

RUDOLPH LIEBMAN. [I. S.]
